United States Patent Office.

JOHN N GRIMM, OF ST. LOUIS, MISSOURI.

Letters Patent No. 96,223, dated October 26, 1869.

IMPROVEMENT IN AIR-BLAST ENGINES.

The Schedule referred to in these Letters Patent and making part of the same

To all whom it may concern:

Be it known that I, JOHN N GRIMM, of St. Louis, in the county of St. Louis, and State of Missouri, have made certain new and useful Improvements in Air-Blast Engines; and I do hereby declare that the following is a full and clear description thereof, reference being had to the accompanying drawings, and to the letters of reference marked thereon.

The nature of this invention is in the arrangement of two bells or cylinders dipping into a cistern of water, and arranged with such valves that when withdrawn from the water, air shall enter, and when forced into the fluid, air shall be forced into the blast-tubing; and said nature is in the general and detail construction of said engine as hereinafter more fully set forth.

To enable those skilled herein to make and use my said invention, I will now fully describe the same, referring to

Figure 1 as a vertical sectional elevation, and to

Figure 2 as a plan.

I construct an enclosing-cistern, A, and place water therein. Within said cistern I arrange the cylinders B, guiding the same by the side guides C, and suspending the same by the connecting-rods D from the walking-beam E, which is journalled at F on the main frame G.

The detail construction of the said parts may be in any usual form, and nothing herein is claimed.

Further, to guide said cylinders B, and to connect more perfectly with the blast-tubes, I arrange the caps H within the cylinders B. The blast-tubes I connect with said caps H. Said blast-pipes are carried to and supported on the bed of the cistern A, and pass to the air-vessel K, from whence a single blast-tube, L, goes to the furnace where the blast is required.

The air-vessel K is used to receive the successive fillings of the cylinders B, and acts by its capacity, both as an air-cushion and pressure-equalizer; so that the air passing out at I is in a more uniform stream.

The air-vessel K may further be arranged with double walls, between which steam, or the hot gases formed by combustion, may be introduced by a pipe, I', for heating the air for the blast.

Again, steam may be introduced directly into the vessel K, in that manner adding vapor and its components, oxygen and hydrogen-gases, to the blast, and thereupon increasing the heat produced in the furnace.

In the heads b, of the cylinders B, I arrange the valves M. These are usually flat hinged plates of iron, being hinged at m, and having the flexible (usually rubber) support m' at the opposite edge.

On the down-stroke of the cylinders B, the air within the same will, by its pressure, close the valves M, and will be forced through the blast-tubes I to the furnace.

The caps H will partly prevent the escape of air, and the water of the cistern A will effectually do the same.

On the up-stroke of the cylinders B, the air will force down the valves M and enter the cylinders B.

This device is peculiarly fitted to supply large quantities of air, and owing to the non-use of packings and stuffing-boxes, there is no need of repair or danger of disorder. At the same time, the air-checking fluid A', of the cistern A, gives up vapor to the air in the cylinders; in other words, the air is moistened; thereby oxygen and hydrogen are brought to the combustion of the furnace, causing extraordinary heat.

From the air-box K, two, three, or more pipes, L, may pass out, delivering the air to several points, either of the same furnace or of different furnaces.

Having thus fully described my invention,

What I claim, is—

The apparatus for forcing air and heating the same, composed of the cylinders B, operated by a beam, E, and connecting with the diaphragms H, pipes I, the heater K, and blast-tube L, when arranged substantially as and for the purposes set forth.

In witness whereof, I have hereunto set my hand, this 11th day of November, A. D. 1868, in the presence of—

JOHN N GRIMM.
